Patented Nov. 28, 1916.

Inventor:
René Colin
By: B. J. Engle, Atty.

UNITED STATES PATENT OFFICE.

RENÉ COLIN, OF STRASSBURG, GERMANY.

SPARK-PLUG.

1,206,788.

Specification of Letters Patent. Patented Nov. 28, 1916.

Application filed November 1, 1915. Serial No. 59,116.

To all whom it may concern:

Be it known that I, RENÉ COLIN, a subject of the Emperor of Germany, and resident of Strassburg, Alsace, Germany, have 5 invented certain new and useful Improvements in Spark-Plugs, of which the following is a complete specification.

My invention relates to a sparking plug which can be inserted in a simple manner 10 and is effectively secured against unintentional displacement during operation. The casing of the plug may be rigidly secured in the motor cylinder or may be made integral therewith, because the casing may be left 15 in position when the plug is taken out. The securing of the plug in a gas-tight manner is effected by means of a groove cam which engages with and presses down shoulders on the plug. By the pressure thus exerted the 20 plug is retained in such a firm manner that it cannot be forced out of place even by the heaviest shocks of the motor, as the pressure acting upon the plug presses the shoulders tightly in the groove in the casing. In 25 order to prevent any unintentional movement or loosening of the plug, a locking device is also provided.

An example of construction according to 30 the invention is illustrated in the accompanying drawing.

Figure 1 shows a section of the sparking plug; Fig. 2 shows a section of the casing thereof; Fig. 3 shows a plan view; Fig. 4 shows a section of the shell of the plug; 35 Fig. 5 shows the current-carrying pin; Fig. 6 shows a front view of the sparking plug; Fig. 7 is a section on line A—B of the Fig. 1.

The casing *a* according to the present example of construction, is screwed tightly 40 into the motor cylinder by a screw thread at *b*. As hereinbefore stated, this casing may be cast in one with the cylinder, or it may be secured thereto in a permanent manner. The casing *a* is provided with an internal 45 shoulder or flange *c* receiving a packing ring *d* which is pressed tightly in position by means of an inner cylinder or shell *e*. This shell *e* is provided with projecting lugs or shoulders *f* and possesses a perforated 50 bottom *x*, in the middle hole of which lies

the end of the pin *n*. The casing *a* is also provided with groove cams *h* which are formed on the under surface of the inwardly turned flange *i*. Slots at *g* extend through this flange and thus permit the 55 shoulders *f* to enter the cam grooves and to be turned to a holding position therein. The shell *e* is provided with an internal shoulder or flange *k* forming the seating of an insulator *l* which is packed by a packing 60 ring *m*. A screw plug or nut *w* screwing into the top *s* of shell *e* locks the insulator *l* therein. The ignition pin *n* is packed in turn in the insulator *l* by means of a ring *o* placed in a recess in the insulator, against 65 which ring an enlargement at *r* on the pin is drawn by means of nuts *p*, which cannot become loose as they are locked in position by the springy expanding end *g* of the pin *n*. The internally screwed top portion *s* of the 70 shell *e* also carries a handle *t* which is retained in position by a spring pawl *u* adapted to engage between projections *v* on the casing *a*, and thus to prevent unintentional turning of the shell *e* in the casing. 75

Having thus described my invention and in what manner the same is to be performed I declare that what I claim is:

A spark plug of the character described comprising in combination, an outer casing, 80 projections on said casing, an inner shell within said casing having a perforated bottom, projecting lugs on said shell, and cam grooves in said outer casing adapted to receive said projections for locking said casing and shell, an inner flange on said shell, an insulator seated upon said flange, a plug screwed into the top of said shell for locking the insulator in its position in said shell, an ignition pin in said insulator extending 85 through the central hole of said perforated bottom, means for securing said pin in its position, a handle secured in the top portion of said shell, and a spring pawl adapted to engage between the projections on said 90 casing for preventing an accidental rotation of the shell. 95

In testimony whereof I affix my signature.

RENÉ COLIN.
